UNITED STATES PATENT OFFICE

SEYMOUR W. FERRIS, OF LANSDOWNE, PENNSYLVANIA, ASSIGNOR TO THE ATLANTIC REFINING COMPANY, OF PHILADELPHIA, PENNSYLVANIA, A CORPORATION OF PENNSYLVANIA

EXTRACTION OF MINERAL OILS

No Drawing.

Application filed May 15, 1931. Serial No. 537,752.

The present invention relates to the art of mineral oil refining, and has particular reference to the separation of crude petroleum or petroleum products into fractions of different chemical compositions while of approximately the same distillation range.

In accordance with my invention, crude petroleum or petroleum products, particularly oils of substantial viscosity, are separated into various fractions by means of fractional extraction with an organic, that is, an aliphatic or aromatic thiocyanate or isothiocyanate or mixture of aliphatic and/or aromatic thiocyanates and/or isothiocyanates, or mixture of solvents containing substantial quantities of aliphatic and/or aromatic thiocyanates and/or isothiocyanates.

It is recognized in the art that mineral oils, such as petroleum, comprise essentially a mixture of hydrocarbons of various groups or homologous series of compounds, such for example, as paraffins of the general formula C_nH_{2n+2} , olefines of the general formula C_nH_{2n} , hydroaromatics and polymethylenes of the same empirical formula, and various other series of compounds of chain and/or ring structures in which the hydrogen to carbon ratio is less than in the foregoing series. A large number of individual components of each series and of differing boiling points are present in petroleum.

The various types of crude petroleum, which are generally classified into three groups, namely, paraffinic base, naphthenic or asphaltic base, and mixed base, contain the various series of hydrocarbons mentioned heretofore in different proportions. For example, in the paraffin base crude oils, such as those obtained from the oil fields of Pennsylvania, there is a relatively high proportion of hydrocarbons having a chain structure and a high hydrogen to carbon ratio, whereas in the naphthenic or asphaltic base crude oils, there is a relatively large proportion of hydrocarbons having ring structures and a low hydrogen to carbon ratio. Mixed base crude oils, such as are obtained from the Mid-Continent oil fields, contain hydrocarbons in proportions intermediate these two extremes.

As the use of practically all of the petroleum oils is almost entirely physical, the above described chemical nature of those oils is important in reflecting certain physical characteristics.

The variance in the proportion of the different series of hydrocarbons in paraffinic, naphthenic, and mixed base oils is evidenced by the physical properties of the various oils and particularly by the relationship of the specific gravity to the viscosity of one oil as compared with another. For example, oils derived from a Pennsylvania crude and having a viscosity of 400 seconds Saybolt universal at 100° F., will show a specific gravity at 60° F. of about 0.878, whereas an oil of corresponding viscosity produced from a naphthenic crude, such as one from the Gulf coast area, will show a specific gravity of about 0.933 at 60° F. The relationship between the viscosity and gravity indicates degree of the paraffinic or naphthenic character of the oil.

If a given crude petroleum be distilled into successive fractions and the specific gravities and viscosities of the several fractions determined, it will be found that they conform to the general relationship:

$$G = a + \frac{1.0752 - a}{10} \log (V - 38)$$

in which "G" is the specific gravity at 60° F., "V" is Saybolt universal viscosity at 100° F., and "a" is a constant known as the viscosity-gravity constant. Fractions from each of the different types of crude have different viscosity-gravity constants. Such constants are lower for fractions of the paraffinic crudes than are the constants for fractions of the naphthenic crudes. An article entitled "The viscosity-gravity constant of petroleum lubricating oils" by J. B. Hill and H. B. Coats which will be found in volume 20, page 641 et seq., Industrial and Engineering Chemistry for June 1928, explains the determination of such constant for several typical oils.

The viscosity-gravity constant is, therefore, an index of the paraffinic or naphthenic character of an oil, since when a given crude is distilled and fractions thereof are collected regardless of the fraction upon which the spe-

cific gravity and the viscosity are taken, when such specific gravity and viscosity are substituted in the formula and the viscosity-gravity constant of the fraction calculated, 5 the constant will be substantially the same for each of the several fractions of the crude.

The viscosity-gravity constants of the viscous fractions for some of the typical crudes are as follows:

10	Milltown (Pennsylvania) -----	0.8067
	Burbank (Mid-Continent) -----	0.8367
	Guadalupe (Gulf coast) -----	0.8635
	Mirando (Gulf coast) -----	0.9025

15 These oils are increasingly paraffinic as the viscosity-gravity constants decrease.

My invention is based upon the discovery that oils containing both the paraffinic series of hydrocarbons and the various naphthenic 20 series may be fractionally extracted with an aliphatic or aromatic thiocyanate or isothiocyanate. Methyl thiocyanate and/or allyl isothiocyanate are the selective solvents that I prefer to use, however, other aliphatic or 25 aromatic thiocyanates or isothiocyanates such as phenyl thiocyanates may be employed, and are considered within the scope of my invention. The various series of hydrocarbons possess a differential solubility 30 in such solvents; the naphthenic hydrocarbons are much more soluble therein than the paraffinic hydrocarbons. By means of extraction with an aliphatic or aromatic thiocyanate or isothiocyanate, and more particu- 35 larly with methyl thiocyanate and/or allyl isothiocyanate, it is, therefore, possible to effect a partial separation of the naphthenic hydrocarbons from the paraffinic, and to obtain from an oil containing both classes of 40 hydrocarbons, an oil which is much more paraffinic than the original oil and one which is much more naphthenic. By my invention, for example, it is possible to produce an oil 45 of the quality normally obtained from Appalachian crudes, from crudes of the mixed base type from the Mid-Continent area, and conversely, to obtain oils from mixed base crudes such as are normally obtained from the naphthenic oils of the Gulf coast area.

50 In practicing my invention, I prefer to mix the oil fraction to be treated with a suitable proportion of an aliphatic or aromatic thiocyanate or isothiocyanate or mixture of them, and more particularly with methyl thiocyanate and/or allyl isothiocyanate, at a temperature sufficiently high so that complete 55 solution is effected and a homogeneous liquid obtained. I then cool the mixture to a temperature sufficiently low to cause a separation 60 of the liquid into a two-layer system, the upper layer being a solution of a relatively small amount of the aliphatic or aromatic thiocyanate or isothiocyanate in the more paraffinic portion of the oil, and the lower 65 layer comprising a solution of the more

naphthenic portion of the oil in the aliphatic or aromatic thiocyanate or isothiocyanate.

Instead of this heating and cooling to effect extraction, I may simply agitate the mixture of liquids at normal temperatures. Where 70 substantially quantities of solid hydrocarbons belonging to the true paraffin series (C_nH_{2n+2}) are present, these solids or waxes remain in the upper layer and may cause it to be solid or semi-solid. Separation of the 75 two layers is then effected, for example, by decantation, and the aliphatic or aromatic thiocyanate or isothiocyanate removed from each of the separated oil layers by vacuum distillation or other suitable procedure, 80 thereby obtaining two oils of similar distillation ranges but of widely different physical characteristics and correspondingly different chemical compositions.

Before removing the aliphatic or aromatic thiocyanate or isothiocyanate from the upper and more paraffinic layer of oil obtained in the above described process, I may add a further quantity of aliphatic or aromatic thiocyanate or isothiocyanate, and repeat the 85 process for an extraction of additional naphthenic bodies from the oil. The extraction may be repeated any desired number of times, thereby producing oils of progressively increasing paraffinity as evidenced by a decreasing viscosity-gravity constant. In wax-bearing oils, the final undissolved product is 90 a mixture of solid and liquid hydrocarbons. While the exact chemical compositions of these compounds are not known, it is probable 95 that the liquid hydrocarbons are branched chain hydrocarbons of the paraffin series, whereas solid bodies are straight chain paraffin hydrocarbons. This product may 100 be further separated into solid and liquid hydrocarbons by any of the well-known dewaxing processes, such as the cold settling process.

105 In many instances it will be found of advantage to dewax the oil prior to the extraction process, as this expedites the manual operation of the latter.

My invention will be further understood from the following specific examples:

110 100 parts of a previously untreated distillate obtained from a Gulf coast crude oil and having a viscosity of 612 seconds Saybolt universal at 100° F., a specific gravity of 0.9303, and a consequent viscosity gravity constant of 0.874 was mixed with 100 parts 115 of methyl thiocyanate and heated to slightly above the temperature of complete miscibility, which in the particular case was approximately 75° C. The homogeneous liquid which resulted was cooled with agitation 120 to 35° C., and allowed to settle whereupon a two layer system formed, which consisted of an upper undissolved oil layer comprising 78.7 parts of the mixture and a lower layer 125 of oil dissolved in methyl thiocyanate com- 130

prising approximately 121.3 parts of the mixture. After separation, the layers were each freed from methyl thiocyanate by vacuum distillation. The methyl thiocyanate dissolved fraction yielded 94.7 parts of methyl thiocyanate and 26.3 parts of oil having a viscosity of 67 seconds Saybolt universal at 210° F., a specific gravity of 0.9854, and a viscosity gravity constant of 0.943. The undissolved fraction yielded 5.3 parts of methyl thiocyanate and 73.4 parts of an oil having a viscosity of 381 seconds Saybolt universal at 100° F., and a specific gravity of 0.9042, and a viscosity gravity constant of 0.846.

10 15 20 25 30 35 40 45 50 55 60 65 70 75 80 85 90 95 100 105 110 115 120 125 130

100 parts of residual stock from a paraffin base crude having a viscosity of 103 seconds Saybolt universal at 210° F. and a specific gravity of 0.8905 and a consequent viscosity gravity constant of 0.808, was mixed with 300 parts of allyl isothiocyanate and heated to slightly above the temperature of complete miscibility which in this particular case was approximately 23° C. The homogeneous liquid which resulted was cooled with agitation to -15° C., and allowed to settle whereupon a two-layer system formed which consisted of an upper undissolved oil layer comprising 90 parts of the mixture. After separation, the upper layer was freed from allyl isothiocyanate by vacuum distillation. This fraction yielded 24 parts of allyl isothiocyanate and 66 parts of an oil having a viscosity of 94 seconds Saybolt universal at 210° F., and a specific gravity of 0.8772, and a consequent viscosity gravity of 0.793.

From the above examples it will be seen that by a methyl thiocyanate and/or allyl isothiocyanate extraction there may be obtained oil fractions which are respectively higher in paraffinic and naphthenic than the original oil. By repetition of the extraction process upon the methyl thiocyanate and/or allyl isothiocyanate undissolved fraction, oils may be obtained which are increasingly paraffinic, as evidenced by progressively decreasing viscosity-gravity constants.

It is evident that my process is practically independent of the particular nature or source of the crude oil, and that there may be produced thereby oils of desired characteristics from oils which heretofore have not been used as a source of oils of such desired characteristics.

For example, my process may be employed to produce from petroleum of a mixed base type such as would, on normal batch distillation, give a residuum with a viscosity of 150 seconds Saybolt universal at 210° F. with a specific gravity of 0.928 or more, a lubricating stock with a viscosity at 210° F., of 150 seconds Saybolt universal, or more, and a specific gravity not higher than 0.910. This latter combination of properties is typical of

cylinder stocks produced from Pennsylvania crudes.

In extracting oils containing appreciable amounts of wax, such oils may be dewaxed, for example, by cold settling or centrifuging prior to carrying out the extraction. My process is operable, however, in the absence of preliminary dewaxing.

Hereinafter, mixtures of solvents have been referred to. It is to be understood that in such mixtures the constituent solvents will not react with one another, nor with the oil upon which they are to be used, and that such mixtures will contain substantial amounts of aliphatic and/or aromatic thiocyanates and/or isothiocyanates.

For brevity, in the appended claims, the term "organic thiocyanate" is employed in a generic sense to include one or a mixture of aliphatic and/or aromatic thiocyanates and/or isothiocyanates, or a mixture of solvents which contains substantial quantities of aliphatic and/or aromatic thiocyanates and/or isothiocyanates.

Also where herein and in the appended claims, an oil is specifically referred to as being "viscous", it is to be understood that the oil is of substantial viscosity, i. e., of the order of 50 seconds Saybolt universal at 100° F., or more.

What I claim is:

1. In the art of refining mineral oils, the process which comprises separating an oil containing paraffinic and naphthenic hydrocarbons into fractions respectively richer in paraffinic and naphthenic compounds by extracting said oil with an organic thiocyanate.

2. In the art of refining mineral oils, the process which comprises fractionally extracting an oil containing paraffinic and naphthenic hydrocarbons with an organic thiocyanate to produce fractions of the oil respectively richer in paraffinic and naphthenic compounds.

3. In the art of refining mineral oils, the process which comprises adding an organic thiocyanate to an oil containing paraffinic and naphthenic hydrocarbons, heating the mixture to such temperature as to effect solution, cooling the solution to form a two layer system, and separating the upper layer from the lower layer.

4. In the art of refining mineral oils, the process which comprises adding an organic thiocyanate to an oil containing paraffinic and naphthenic hydrocarbons, heating the mixture to such temperature as to effect solution, cooling the solution to form a two layer system, removing the lower layer, and similarly retreating the upper layer with an organic thiocyanate.

5. In the art of refining mineral oils, the process which comprises bringing a mineral oil containing paraffinic and naphthenic hydrocarbons into contact with a thiocyanate,

thereby to effect solution of a portion richer in naphthenic hydrocarbons in the thiocyanate, separating the solution so formed from the remainder of the oil, and removing the thiocyanate from both portions of the oil, thereby to obtain fractions of the oil respectively richer in paraffinic and naphthenic hydrocarbons.

6. The process for separating mineral oils containing paraffinic and naphthenic hydrocarbons into fractions which comprises bringing the oil into contact with an organic thiocyanate, thereby to effect solution of a portion of the oil richer in naphthenic hydrocarbons in the organic thiocyanate, separating the solution so formed from the remainder of the oil, and distilling the organic thiocyanate from both of the portions of the oil, thereby to obtain fractions of the oil respectively richer in paraffinic and naphthenic hydrocarbons.

7. In the art of refining mineral oils, the process which comprises bringing a mineral oil containing paraffinic and naphthenic hydrocarbons into contact with an organic thiocyanate, thereby to effect solution of a portion richer in naphthenic hydrocarbons in the organic thiocyanate, separating the solution so formed from the remainder of the oil, and retreating the oil remaining with additional amounts of an organic thiocyanate.

8. The method of producing paraffinic lubricating oil from mixed base crude which comprises distilling the crude and bringing a portion thereof into contact with one or more solvents from the group consisting of methyl thiocyanate and allyl isothiocyanate, thereby partially dissolving the oil, separating the solvent solution of oil so treated, and removing the solvent from the treated oil.

9. The process of producing a lubricating stock of specific gravity less than .910 and of Saybolt universal viscosity greater than 150 seconds at 210° F. from a crude petroleum which on normal distillation yields a residuum of 150 seconds Saybolt universal viscosity at 210° F. and a specific gravity greater than .928, which comprises producing a residuum from the crude petroleum, and extracting said residuum from said crude petroleum with one or more solvents from the group consisting of methyl thiocyanate and allyl isothiocyanate.

10. In the art of refining mineral lubricating oil containing paraffinic and naphthenic hydrocarbons, the step of fractionally extracting the oil with one or more solvents from the group consisting of methyl thiocyanate and allyl isothiocyanate, to effect a separation of fractions respectively richer in paraffinic and naphthenic compounds.

11. The process of producing a lubricating stock of specific gravity less than .910 and of Saybolt universal viscosity greater than 150 seconds at 210° F. from a crude petroleum

which on normal distillation yields a residuum of 150 seconds Saybolt universal viscosity at 210° F. and a specific gravity greater than .928, which comprises separating a residuum from said crude petroleum and bringing such residuum into contact with one or more solvents from the group consisting of methyl thiocyanate and allyl isothiocyanate, to effect solution of a portion thereof with the solvent, separating the solvent solution of oil from the portion which does not dissolve therein, and removing the solvent from the oil of said solution.

12. In a process for separating a viscous mineral oil containing paraffinic and naphthenic hydrocarbons into fractions which are respectively richer in naphthenic hydrocarbons and paraffinic hydrocarbons other than wax, the step which comprises extracting the oil with one or more solvents from the group consisting of methyl thiocyanate and allyl isothiocyanate.

13. In a process for separating viscous mineral oil liquid at ordinary temperature containing paraffinic and naphthenic hydrocarbons into fractions respectively richer in paraffinic and naphthenic hydrocarbons, the step which comprises extracting the oil with one or more solvents from the group consisting of methyl thiocyanate and allyl isothiocyanate.

14. In a process for separating a substantially wax free viscous mineral oil containing paraffinic and naphthenic hydrocarbons into fractions respectively richer in paraffinic and naphthenic hydrocarbons, the step which comprises extracting the oil with one or more solvents from the group consisting of methyl thiocyanate and allyl isothiocyanate.

15. The process of treating a viscous fraction of a crude oil of one type containing paraffinic and naphthenic hydrocarbons to procure a fraction having the quality of a corresponding fraction of a crude oil of different type having a greater content of paraffinic hydrocarbons, which comprises extracting the viscous fraction with one or more solvents from the group consisting of methyl thiocyanate and allyl isothiocyanate, and separating the oil so treated into portions respectively richer in paraffinic and naphthenic hydrocarbons.

16. The process of treating a viscous fraction of a mixed base crude oil to procure a fraction having the quality of a corresponding fraction of a paraffinic base crude, which comprises extracting the viscous fraction with one or more solvents from the group consisting of methyl thiocyanate and allyl isothiocyanate, and separating the oil so treated into portions respectively richer in paraffinic and naphthenic compounds.

17. In the art of refining mineral oils, the process which comprises adding one or more solvents from the group consisting of methyl

DISCLAIMER

1,874,947.—*Seymour W. Ferris*, Lansdowne, Pa. EXTRACTION OF MINERAL OILS.
, Patent dated August 30, 1932. Disclaimer filed February 15, 1934, by
the assignee, *The Atlantic Refining Company*.

Enters this disclaimer, to wit:

Petitioner disclaims from the scope of claims of the patent aforesaid, the process for separating viscous mineral oil liquid at ordinary temperatures containing paraffinic and naphthenic hydrocarbons into fractions respectively richer in paraffinic and naphthenic hydrocarbons, by extraction of the oil with methyl thiocyanate ($\text{CH}_3\text{S.C.N}$).

Petitioner specifically disclaims from the scope of claim 13 of said patent, the words "one or more solvents from the group consisting of methyl thiocyanate and".

[*Official Gazette March 6, 1934.*]
